UNITED STATES PATENT OFFICE

EARLE R. SMITH, OF ALHAMBRA, CALIFORNIA

DESIGN FOR A CARPET SWEEPER

Application filed April 15, 1930. Serial No. 35,253. Term of patent 3½ years.

To all whom it may concern:

Be it known that I, EARLE R. SMITH, a citizen of the United States of America, residing at Alhambra, in the county of Los Angeles and State of California, have invented a certain new, original, and ornamental Design for Carpet Sweepers, of which the following is a specification, reference being had to the accompanying drawing, forming part thereof.

In the accompanying drawing,
The figure is a perspective view of a carpet sweeper, showing my new design.

I claim:
The ornamental design for a carpet sweeper, as shown.

EARLE R. SMITH.
